ATTORNEY

UNITED STATES PATENT OFFICE.

JOHN A. CARRIGAN, OF NEW CASTLE, PENNSYLVANIA.

ATTACHMENT FOR METAL-COATING MACHINES.

1,348,478.

Specification of Letters Patent.

Patented Aug. 3, 1920.

Application filed August 3, 1917, Serial No. 184,348. Renewed April 21, 1920. Serial No. 375,658.

To all whom it may concern:

Be it known that I, JOHN A. CARRIGAN, a citizen of the United States, residing at New Castle, in the county of Lawrence and State 5 of Pennsylvania, have invented certain new and useful Improvements in Attachments for Metal-Coating Machines, of which the following is a specification.

This invention relates to metal coating 10 machines, and the invention has more special reference to novel sheet wiping means.

The invention has for its principal object to provide a wiping attachment for metal coating machines, whereby any surplus coating 15 material remaining upon the sheet subsequent to the immersion thereof in the metal bath will be removed, thereby affording a smoothly surfaced and finished product and 20 eliminating the waste of the coating material.

The invention also embodies means whereby the wiping attachment, which is rotatably mounted upon the galvanizing or tinning pot of the coating machine will be 25 driven at a rate of speed slightly less than the speed of the rotary feed-out rollers, thus efficiently and constantly changing the wiping surface.

Among other aims and objects of the invention may be recited the provision of an 30 attachment of the character mentioned with a view to compactness and in which the number of parts are few, the construction simple, the cost of production small, and 35 efficiency and operation high.

All of the foregoing, together with additional advantageous details and arrangement of parts of the preferred embodiment of my invention will be clear from the specific 40 description hereinafter contained, when read in connection with the accompanying drawings forming a part thereof, wherein said embodiment of the invention is illustrated for the purpose of facilitating a full 45 understanding of the present improvements.

In the drawings,

Figure 1 is a longitudinal section in elevation through a metal coating machine having my improved sheet-wiping attachment 50 thereon; and

Fig. 2 is a side elevation of the machine showing the manner in which the wiping attachment is driven by the feed-out rollers of the machine.

Similar characters of reference are em-

ployed in all of the above described views to indicate corresponding parts.

Referring now more particularly to the several figures of the said drawings, I have shown by way of illustration the present 60 improvements as applied to a form of metal coating machine now marketed, wherein the tin, spelter or other coating material is contained by a pot 1, which pot has arranged therein a plurality of guides, indicated by 65 the numerals 2 and 3, the latter as will be noted being spaced from the former to permit circulation of coating material therethrough. To support the forward ends of the guide-ways 2, a strut 4 is arranged upon 70 the bottom of the pot 1 and is adapted to receive the said guide ways thereupon. The guide ways 3 are directed into the bite by a plurality of feed-out rollers 5 and 6, it being noted that two sets of the rollers are em- 75

ployed, namely, an upper set and a lower set. Thus, when the coated material is fed into the bite of the lower set, it will be fed upwardly into engagement with the upper set and then delivered onto a suitable sup- 80 port or receiving tray. The feed-out rollers 5 and 6 are journaled in bearings formed within the side walls of the pot 1 and have arranged upon certain of the ends thereof a plurality of meshing gears 7, these gears 85 providing means whereby the feed-out rollers may be driven.

With more special reference to the present improvements, there is provided a plurality of sets of wiping rollers 8 and 9, which 90 rollers may be and preferably are formed from an absorbent material, such as asbestos, felt, or the like and have embedded therein a wire mesh reinforce, which, obviously, will maintain the same in proper 95 condition. Slightly larger meshing gears 10 are arranged upon the ends of the supporting shafts of the wiping gears 8 and 9 adjacent the gears 7 and to connect the same with the said gears 7 whereby they may be 100 driven at a rate of speed slightly less than the speed of the feed-out rollers 5 and 6, smaller gears 11 are in mesh with the several sets of the upper feed-out rollers and the gears 10 of the wiping rollers. By this ar- 105 rangement, it will be understood that upon rotation of the feed-out rollers, such motion will be necessarily imparted to the wiping rollers 8 and 9. However, due to their connection with the said feed-out rollers, the 110

wiping rollers will rotate at a slower rate of speed.

It will also be noted that the pot 1 is provided with an inner depending wall 1' which extends below the upper surface of the pot, as shown in Fig. 1. This wall 1' is in direct alinement with the stud 4, although its lower end is spaced therefrom to provide a communication upon each side thereof. It will be noted that the guide ways are so provided that the upper guide way 2 communicates with its respective guide way 3 in such manner as to permit the coating liquid upon one side of the wall 1' to pass thereinto, although the lower guide way communicates with its respective guide way 3 upon the opposite side of the wall, thus causing the coating liquid in this side of the pot to be used, thus causing a thorough circulation and the equal using of the liquid. It will further be noted that the guide ways 2 and 3 taper gradually throughout their entire length toward the direction of the rollers, thus coating the sheet material which is being passed through the guide ways so that it will carefully engage the rollers. It will be noted that the guide ways 3 have their lower ends out turned as indicated at 3', preventing the hanging of the sheet material upon the ends of the guide ways 3, owing to the out turned ends above specified being carried very near to the lower end of the guide way 2.

The operation of the construction may be reviewed as follows: A sheet of metal is fed into certain of the guideways 2 and is directed thereby downwardly into the metal bath. During movement of the sheet through the bath, it will be efficiently coated and fed upwardly by the remaining guideways 3 into the bite of the lower feed-out rollers 5 and 6. Should any surplus material remain upon the sides of the metal sheet, the same when engaged between the wiping rollers 8 and 9 will be removed and returned to the pot 1, whereupon the sheet will be then engaged with the upper feed-out rollers and delivered onto the weighing tray or other receiving device. By rotating the rollers 8 and 9 at a rate of speed slightly less than the speed at which the feed-out rollers are rotated, it is evident that a slight drag will be imparted by the said rollers 8 and 9 to the coated sheet, hence thoroughly and efficiently removing such surplus coating material as may remain upon the sides thereof. Furthermore, by rotating the rollers 8 and 9 a constantly changing wiping surface is afforded, thereby preventing the streaking or uneven wiping of the sheets and rendering a smoothly surfaced and finished product.

From the foregoing, it will be appreciated by workers in the art that I have pro-

vided a wiping attachment which embodies the necessary qualities incident to an attachment of this nature and will prevent extensive waste of coating material. Also, it is to be understood that the device may be equally well adapted upon any form of metal coating machines, irrespective of the fact that the same does not employ rotatable feed-out rollers, such as disclosed in a machine chosen for the present illustration.

As hereinbefore indicated, I do not wish to be understood as confining the invention to the particular embodiment chosen for illustration herein, nor to the exact construction, arrangement and adaptation of the parts shown and described, but I reserve the right to make any changes and alterations that fairly fall within the spirit and scope of the invention.

What I claim is:

1. In a device of the class described, the combination of a supporting means, pairs of feed-out rollers rotatably supported upon said supporting means, the rollers of each pair being contiguous to each other, while said pairs are spaced from each other, wiping rollers rotatably mounted upon said supporting means, said wiping rollers being interposed between pairs of the feed-out rollers, means for rotating the feed-out rollers at a uniform speed, and means for rotating the wiping rollers in the same direction as that of the feed out rollers and slower than the feed-out rollers, thus causing a sheet of metal to positively pass out between the feed out rollers and the wiping rollers.

2. In a device of the class described, the combination of a supporting means, pairs of feed-out rollers rotatably supported upon said supporting means, the rollers of each pair engaging each other under normal conditions, said pairs being spaced apart, wiping rollers rotatably supported upon said means and interposed between said feed-out rollers, meshing gears of uniform sizes connected to said feed-out rollers, enlarged gears connected to said wiping rollers, and gears so meshing with the gears of the feed-out rollers and wiping rollers, as to cause the wiping rollers to rotate in the same direction as the feed-out rollers, but at a reduced speed, thus causing the wiping rollers to have a slight dragging action upon a sheet of material moved outwardly between the feed-out rollers to evenly coat such material.

In testimony whereof I affix my signature in presence of two witnesses.

JOHN A. CARRIGAN.
